UNITED STATES PATENT OFFICE.

OLOF NELSON, OF ATTLEBORO, MASSACHUSETTS, ASSIGNOR TO THE ROBBINS COMPANY, OF ATTLEBORO, MASSACHUSETTS, A CORPORATION OF RHODE ISLAND.

NAME-PLATE ATTACHMENT.

1,390,637.

Specification of Letters Patent. Patented Sept. 13, 1921.

Application filed July 5, 1921. Serial No. 482,461.

To all whom it may concern:

Be it known that I, OLOF NELSON, a citizen of the United States, residing at Attleboro, in the county of Bristol and State of Massachusetts, have invented certain new and useful Improvements in Name-Plate Attachments, of which the following is a specification.

My invention is an improved means for connecting a name or emblem plate or the like to any desired supporting surface. The immediate and particular object I have in view is to secure a name or emblem plate upon the shell or cover of the radiator of an automobile. This radiator shell is in effect a cover for the radiator proper, which is a cellular or tubular element, through which the heated water from the water jackets of the motor cylinders is passed to disperse heat units to the air, and the shell fits the radiator closely, so that it is difficult or impossible to insert hands or tools between the shell and the radiator or to get at the inner surfaces of the shell without removing the shell from the radiator.

In the drawings:

Figure 1 is a central section of the upper part of an automobile radiator, showing the shell covering the same, with a name plate attached;

Fig. 2 is a rear view of a name plate, with its attaching device;

Fig. 3 is a perspective view of the attaching device;

Fig. 4 is a section on line 4—4 of Fig. 2;

Fig. 5 is a section on line 5—5 of Fig. 2;

Fig. 6 is a plan or front view of the plate or shell member, with aperture formed therein;

Fig. 7 is the same, after pressing the bridges back;

Fig. 8 is a cross-section on line 8—8 of Fig. 7;

Fig. 9 is a rear view of the name plate, attached;

Fig. 10 is a section on line 10—10 of Fig. 9;

Fig. 11 is a cross-section on line 11—11 of Fig. 7;

Fig. 12 is a cross-section on line 12—12 of Fig. 9;

Fig. 13 is a perspective, similar to Fig. 3, of a modified form of attaching device; and

Fig. 14 is a view similar to Fig. 9, but employing the attaching device of Fig. 13.

My connector is made in two parts and the engagement between the two parts is a positive locking engagement, and is not merely a frictional engagement. The engagement and locking is accomplished by the interaction of the parts themselves, when they are brought together. The result is that the engagement is effected with the utmost simplicity and is positive, so that the vibration of the machine, in use, has no effect whatever upon the union of the parts, which retain their engagement until force is designedly applied between the parts in the direction of the longitudinal axis of the automobile, to separate them.

In the preferred form of my device, I provide a tang member, which is shown in Fig. 3. The member is struck up from a blank, to bend the four arms, as shown in Fig. 3. The short arms *a*, which are preferably shaped to a curved outline at their free ends, are bent to a right angle with the central portion of the blank. The long arms *b* are bent to an angle of less than 90° with the central portion of the blank, preferably to an angle of about 55°. The central portion *c*, is then secured by soldering or otherwise, to the back of the name or emblem plate *d*, which is to be attached or connected.

In another plate, or preferably in the substance of the front of the radiator shell *e*, at the desired point, I form three apertures *f* and *g*, substantially as shown in Fig. 6. The metal within the dotted lines, Fig. 6, is then depressed slightly, leaving the surfaces within the dotted lines slightly lower than the surrounding surfaces (see Figs. 7, 8 and 11). The central square aperture *f*, is of a size to receive the short tangs *a*, along and against its upper and lower edges, the width of these short tangs being equal to the width of the upper and lower sides of the square aperture. The ends of the short tangs are preferably curved, so that in applying the name plate, these short tangs enter the large aperture and serve a preliminary purpose in centering and positioning the tangs and plate. The ends of the long tangs *b*, which stand at an angle to the back of the plate, less than 90° as shown in Fig. 5, encounter the depressed surfaces or bridges *h*, and, as pressure is applied to the name plate, the ends of the long tangs spread apart, and pass into the narrow slots *g*, and as pressure is continued the tangs

bend more and more back to their original position relative to the central portion of the tang member, as shown in Fig. 12, that is, they are flattened out, with their free ends 5 extending through the slots *g*, along the inner side of the plate *d*, in which the slots are formed. In Figs. 13 and 14, I show a tang member having four tangs and a plate member having four narrow slots to receive 10 the four tangs as they are bent in the process of forcing the name plate, with its connected tang member, to a locking engagement. This embodiment of my invention is not in substance different from the preferred form 15 in the means and method of locking the parts together. It lacks, however, the guiding and centering action which is present in the preferred form due to the action of the short tangs *a*, perpendicular to the surface 20 of the back of the name plate. A further reason for preferring the construction described above as preferred, is that more force is required to bend and interlock four locking tangs than is required for two, assuming the sheet metal is of the same gage 25 in both cases. As the two locking tangs, plus the short tangs, give a perfectly secure connection and provide against any movement of the plate, longitudinal, lateral, vertical or rotative, and require less force in 30

application, they are naturally to be preferred even if the preferred form had no other advantage.

The metal employed for the tang members is flexible, but practically non-resilient. 35 I claim:

1. The attaching device above described, consisting of a pair of tangs, their free ends spreading from a common center in opposite directions, and a second pair of tangs perpendicular to the back of the plate to be attached, both pairs of tangs being secured upon the back of the plate to be attached; a socket member having apertures to receive the said tangs and surfaces against 40 which the spreading ends of the one pair of tangs impinge, in application, to spread said tangs into locking position, and guide them to the tang receiving apertures. 45

2. The attaching device above described, 50 consisting of a pair of tangs, their free ends spreading from a common center, in opposite directions, and a second pair of tangs perpendicular to the back of the plate to be attached, both pairs of tangs being secured 55 upon the back of the plate to be attached.

Signed at Attleboro, Massachusetts, this 28th day of June, 1921.

OLOF NELSON.
